1

This invention relates to apparatus for indicating the amplitude or phase versus frequency characteristic of a radio frequency circuit included in, for example, an amplitude modulated radio or television transmitter, the object of the invention being to provide improved apparatus for this purpose.

According to the invention, there is provided apparatus for indicating the amplitude or phase-versus-frequency characteristic of a radio frequency circuit comprising means for feeding to said circuit first oscillations, means for generating second oscillations of a cyclically variable frequency, means for modulating said first oscillations by said second oscillations, mixing means, means for generating third oscillations of a variable frequency having the same frequency difference from the lower sideband and the upper sideband respectively of the modulated first oscillations during alternate cycles of variations of said second oscillations, means for feeding said modulated oscillations and said third oscillations to said mixing means to obtain fourth oscillations at said difference frequency, a cathode ray tube and means for deflecting the beam of said tube along one axis in accordance with the frequency of said third oscillations and along another axis in accordance with signals derived from said fourth oscillations. It will hereinafter appear that the present invention leads to the advantage that the upper sideband response and the lower sideband response of the radio frequency circuit are alternately displaced by the cathode ray tube without risk of ambiguity.

In order that the said invention may be clearly understood and readily carried into effect, the same will now be more fully described with reference to the accompanying drawings, Figures 1 to 3 of which are block diagrams illustrating respectively the application of the invention to the investigation of the characteristics of the sidebands of a transmitter, the modulator of a transmitter, and the R. F. section of a transmitter respectively, and

Figure 4 is a block diagram which illustrates the invention as applied to the investigation of the phase or phase error of a transmitter.

Referring to Figure 1, let F_c be the carrier frequency of a transmitter 1 and F_m the modulation frequency of the transmitter. In order to test the frequency response of the transmitter, F_m must be varied from zero to the maximum modulation frequency F_m required for the test. In practice it is convenient to choose F_m some-

2

what greater than the normal pass-band of the transmitter so that the ends of the characteristic may be examined. A variable frequency oscillator 2 is arranged to have an output frequency F_w which is varied cyclically, the centre frequency of F_w being F_c+F_d , the lower limit being $F_c+F_d-F_m$ and the upper limit being $F_c+F_d+F_m$. The actual value of F_d will be dealt with later but it will in general be a small fraction of F_m . The output from oscillator 2 is fed into a mixer 3, to which are also fed oscillations of a fixed frequency F_c+F_d obtained from an oscillator 4, the amplitude of these oscillations being small compared with that of the oscillations of frequency F_w from oscillator 2. The mixer 3 is arranged to give an output at the difference frequency between the two input frequencies. The difference frequency between the two input frequencies will be F_m and since the frequency F_w in the course of its cyclic variation between its frequency limits passes through the fixed frequency F_c+F_d obtained from the oscillator 4, one cycle of variation of F_w has twice the period of the cyclic variation of F_m and it traverses twice the frequency range. This output is fed into a low-pass filter 5 which has a cut-off frequency somewhat greater than F_m . The output from filter 5 is fed to the modulation input terminals of the transmitter 1 and is of frequency F_m .

In operation, as F_w varies from one extreme to the other F_m will change from F_m down to zero and up again to F_m . The amplitude of F_m should be independent of its frequency, except for a small region near zero, and mixer 3 and filter 5 must be designed with this in mind. In order to reduce still further any change of amplitude, a portion of the output from filter 5 is rectified by a rectifier 6 and fed back into oscillator 4 in such a way as to stabilise the amplitude of F_m . The oscillations F_m will modulate the output of the transmitter 1 so that the output of the latter will consist of three frequencies namely F_c the carrier, F_c-F_m the lower sideband and F_c+F_m the upper sideband, and it is the amplitude of the two sidebands that it is desired to investigate separately. A small portion of the output from transmitter 1 is therefore fed to a mixer 7, which is also fed with some of the output from oscillator 2 (of frequency F_w) to give an output of the difference frequency between its two inputs. The output from mixer 7 is fed to a bandpass filter 8 the centre frequency of which is F_d so that the only frequencies coming from transmitter 1 that will influence the output voltage

from filter 3 will be those having a difference of about F_d from F_w . If F_w is at its lower limit, that is to say $F_w = F_c + F_d - F_m$, the modulation input frequency to the transmitter F_m will be F_m . The output from transmitter 1 will consist instantaneously of three frequencies namely $F_c - F_m$, F_c and $F_c + F_m$. The only one of these frequencies that differs from F_w by F_d is the lower sideband $F_c - F_m$. If mixer 7 is carefully designed the output of frequency F_d from filter 8 will be proportional to the amplitude of the lower sideband of the output of transmitter 1. As F_w is increased in frequency F_m will become lower in frequency until it reaches zero when $F_w = F_c + F_d$, but the difference between F_w and the lower sideband will remain constant at F_d . The amplitude of the oscillations of frequency F_d from filter 8 will therefore remain proportional to the amplitude of the lower sideband. As F_w is still further increased from $F_c + F_d$ towards $F_c + F_d + F_m$ the frequency of F_m will increase again from zero to F_m . The difference frequency between F_w and the upper sideband of the transmitter output will now be constant and equal to F_d , so that the amplitude of the output from filter 8 will now be proportional to the upper sideband. It will thus be appreciated that the elements 3, 4 and 5 constitute means for generating oscillations F_m of a cyclically varying frequency and these oscillations are applied to the transmitter 1 to modulate the carrier wave F_c . The element 2 constitutes means for generating other oscillations F_w which, by virtue of the fact that their frequency is cyclically variable with half the periodicity of the frequency variation of the oscillations F_m and covers twice the frequency range, have a frequency difference F_d from the lower sideband of the lower modulated carrier wave during alternate cycles of the oscillations F_m and have the same frequency difference F_d from the upper sideband during the intervening cycles of the oscillations F_m . The filter 8, moreover, transmits substantially only frequency difference F_d from the mixer 7.

The output from filter 8 is amplified by the amplifier 9, the output from which is rectified by rectifier 10 and then again amplified by the D. C. amplifier 11 and finally applied to the vertical deflection plates of a cathode ray tube 12. The vertical deflection of the beam of said tube will therefore be proportional to the amplitude of the sidebands, except for three frequency bands where the output from filter 8 will not be proportional to only one of the sidebands. These bands will occur when either the carrier or the unwanted sideband is different from the wanted sideband by an amount equal to about 2 F_d , so that they will also produce difference frequencies in mixer 7 of about F_d and will affect the output from filter 8. If, however, the value of F_d and the bandwidth of filter 8 are carefully chosen then these bands may be made narrow and close to the carrier frequency so that they spoil the measurements only at relatively unimportant frequencies.

In order to make the vertical deflection of the beam of the cathode ray tube 12 vary linearly with the amplitude of the sideband it is necessary for the output F_d from mixer 7 to vary linearly with the amplitude of the sideband from transmitter 1. This may be accomplished by arranging for the input to mixer 7 from oscillator 2 to be large compared with the input from transmitter 1 and also arranging that the amplitude of the output of oscillator 2 remains as nearly as possible

constant over the frequency range. In order to ensure that this is so, some of the output from oscillator 2 is rectified by a rectifier 13 and the output from rectifier 13 is fed back to oscillator 2 in such a way as to oppose any variations in the amplitude of F_w .

In order to obtain the horizontal deflection of the cathode ray tube beam some of the output from oscillator 2 is fed into a frequency discriminator 14 which is constructed to give a substantially linear output with frequency over the band over which F_w varies. The output from discriminator 14 is amplified by a D. C. amplifier 15 and fed to the horizontal deflection plates of the cathode ray tube 12. As F_w varies from one extreme to the other the cathode ray tube will show the amplitude versus frequency characteristics of both of the sidebands.

In order to measure the frequency of any part of the characteristics accurately with respect to F_m some of the output from filter 5 (of frequency F_m) is fed into a mixer 16. The other input to mixer 16 is obtained from a calibrated oscillator 17. This oscillator is accurately calibrated over the range of F_m , that is from a low frequency up to F_m . The mixer 16 is designed to give an output difference frequency between its two inputs, and said output is fed into a low-pass filter 18, the bandwidth of this filter being quite small so that a voltage will appear at its outward circuit only when the output frequency from oscillator 17 is nearly equal to F_m . The output from filter 18 is rectified by a rectifier 19, then amplified by an amplifier 20 and applied to the control electrode of the cathode ray tube 12. As F_m varies through its frequency range a pulse will be applied to said control electrode when F_m passes through the frequency to which oscillator 17 is tuned. This pulse can be arranged either to brighten or darken the trace of the cathode ray tube, thus providing a marker point on the characteristics.

It is advantageous to keep the number of complete sweeps per second of the cathode ray beam to as low a value as is consistent with producing a picture on the cathode ray tube screen that does not flicker excessively. There may for example be 100 sweeps per second, oscillator 2 having a frequency of variation F_s of about 50 cycles per second since the cathode ray tube will produce two complete sweeps per cycle.

In order that the amplitude characteristic may be correctly delineated on the cathode ray tube, the frequency response of rectifier 10 and amplifier 11 must be constant up to a frequency considerably higher than F_s . A hundred times F_s would be sufficient which means that the said response must be flat up to 5 kc./s., but it is not difficult to provide a wider band than this if required.

The rectifier 10 must have some smoothing means at its output side so that the input frequency to rectifier 10 (F_d) must be large compared with 5 kc./s. A factor of ten would be sufficient; thus the minimum frequency for F_d is 50 kc./s. The frequency F_d , however, depends on the difference between the carrier frequency F_c of the transmitter 1 and the frequency of oscillator 4 and, since neither of these will be perfectly stable, allowance must be made for their drift so as to ensure that F_d never falls below 50 kc.

If both transmitter 1 and oscillator 4 are crystal controlled they can easily be made to have a

frequency which is stable to 50 parts in 10^6 , so that F_d should have a centre value of

$$50,000 + 2F_c \times \frac{50}{10^6}$$

to allow for the maximum drift. If the apparatus is designed for a maximum F_c of 200 mc./s.

$$F_d = 50,000 + \frac{2 \times 200}{10^6} \times 50 \times 10^6 = 70 \text{ kc./s.}$$

The passband of filter 8 and amplifier 9 must be centred at F_d and be wide enough to allow for both the modulation (5 kc./s.) and the frequency drift (20 kc./s.). It should be noted that it is an advantage to keep F_d as low as possible and the passbands of parts 8 and 9 as small as possible. This is in order to reduce the unwanted effects near the carrier frequency when both sidebands, or the carrier and one sideband, produce frequencies which will pass through filter 8 and amplifier 9.

In a particular example of this apparatus F_c is 62 mc./s., F_m is 8 mc./s., F_d is 0.1 mc./s. and the passband of filter 8 and amplifier 9 is from 50 to 150 kc./s.

Referring now to Figure 2, which shows the invention applied to the testing of the modulation frequency part only of the transmitter, reference numeral 21 indicates the modulation frequency equipment under test, the input frequency F_m being fed thereto in the same way as in the case of a complete transmitter. The output from equipment 21 is fed into an artificial load 22 and a small part of it is also fed to a mixer 23, which is also fed with a carrier wave of frequency F_c derived from an independent oscillator 24 so that the units 23 and 24 now behave in exactly the same way as would the R. F. stages of the transmitter. The output from mixer 23 is fed into mixer 7 and measurements can be made in exactly the same way as before. Care must of course be taken to ensure that mixer 23 does not itself introduce any error.

In this case the cathode ray tube 12 will still produce two characteristics corresponding to the two sidebands, but these of course will be identical. If desired the carrier wave may be derived from the oscillator of the transmitter instead of an independent oscillator.

The arrangement of Figure 3 is similar to that shown in Figure 2, the only difference being that the R. F. section 25 of the transmitter, which is the section to be tested in this case, is connected to the output circuit of mixer 23 instead of to the input circuit thereof. The operation is similar to that of the arrangement of Figure 2.

In certain cases television equipment will not function properly without pulses corresponding to synchronising pulses, since these are necessary for the D. C. restoration and black level clamp. A suitable pulse adding device may be connected between filter 5 and the apparatus under test when necessary. If the added pulses are not synchronous with F_s they will not seriously affect the working of the apparatus, and the pulse will not be seen clearly on the cathode ray tube.

So far the invention has been described as employed for measuring the amplitude versus frequency response of a transmitter or allied apparatus. Figure 4 shows an arrangement for indicating the phase or phase error of apparatus under test. By phase error is meant the amount by which the phase between the input and output differs from a linear relation to frequency. In

the arrangement shown in Figure 4 the output from filter 8 is fed into an amplifier and limiter 26 which feeds a signal of constant amplitude and frequency F_d into a mixer 27 (which replaces rectifier 10 of Figure 1). In addition oscillations of frequency F_c are taken from the oscillator in transmitter 1 and fed into a mixer 28, which is also fed with some of the output from oscillator 4 of frequency $F_c + F_d$. Mixer 28 gives an output of the difference frequency between its two inputs which is passed through a filter 29 which gives an output of frequency F_d , which is fed through a variable time delay network 30 into the mixer 27. Both the inputs to mixer 27 will therefore be of frequency F_d but the input from network 30 will have a phase which is independent of the frequency F_w of the output from oscillator 2, while the phase of the input from amplifier 26 will depend on the phase characteristic of the apparatus under test. The mixer 27 is used as a phase discriminator, that is to say, it gives an output which is proportional to the cosine of the phase difference between its two inputs. The output from mixer 27 is applied to the vertical 10 deflection plates of the cathode ray tube 12 via the amplifier 11, so that the vertical deflection of the trace will also be proportional to the cosine of said phase difference. If the time delay network 30 is adjusted to have zero time delay, the beam will draw a curve representative of the phase response of the apparatus under test. If network 30 is adjusted to have a time delay equal to the low frequency time delay of the apparatus under test, then the beam will trace a curve of the cosine of phase error versus frequency.

The equipment of Figure 4 may be modified for measuring the phase characteristic of the radio frequency or modulation frequency portion of the transmitter separately in the same way as it is modified as shown in Figures 2 and 3 for measuring the amplitude versus frequency characteristics of said portions.

What I claim is:

1. Apparatus for indicating the amplitude or phase-versus-frequency characteristic of a radio frequency circuit, comprising means for feeding to said circuit first oscillations, means for generating second oscillations of a continuously variable frequency, means for amplitude modulating said first oscillations by said second oscillations, mixing means, means for generating third oscillations of a variable frequency having the same frequency difference from the lower sideband and the upper sideband respectively of the modulated first oscillations during alternate cycles of variation of said second oscillations, means for feeding said modulated oscillations and said third oscillations to said mixing means to obtain beat frequency oscillations, filter means for selecting beat frequency oscillations of a predetermined frequency from said mixing means, a cathode ray tube, and means for deflecting the beam of said tube along one axis in accordance with the frequency of said third oscillations and along a second axis in accordance with signals derived from said beat frequency oscillations.

2. Apparatus according to claim 1 including rectifying means for rectifying said beat frequency oscillations, and means for feeding signals derived from said rectifying means to said cathode ray tube to deflect said beam in accordance with the amplitude of said fourth oscillations.

3. Apparatus according to claim 1 including further mixing means, means for feeding said beat frequency oscillations to said further mix-

ing means, means for also feeding to said further mixing means oscillations of the frequency of said heat frequency oscillations but having a fixed phase, means for obtaining from said further mixing means signals having an amplitude dependent on the relative phase of said oscillations fed to said further mixing means, said last named signals being fed to said cathode ray tube to deflect said beam along said second axis.

4. Apparatus according to claim 3 including a variable time delay network, and means for feeding said beat frequency oscillations of fixed phase through said delay network prior to feeding said oscillations to said further mixing means.
